MACHINE FOR GRINDING THE INNER SUR-
FACES OF CYLINDERS OR THE LIKE

Karl Jung, Berlin, Germany

Application August 27, 1932, Serial No. 630,713
In Germany November 21, 1931

5 Claims. (Cl. 51—105)

This invention relates to machines for grinding the inner surfaces of cylinders or the like and has for its object to provide an improved construction thereof. In order to obtain greater precision in machines of this type, it has been proposed hitherto to adjust the tool by swinging its spindle on a swinging arm the axis of which is parallel to the axis of the piece to be worked. In the already known arrangements the swinging axis is also used for moving the grinding disc forward in the direction of its rotating axis and the swinging movement serves for the whole feeding or adjustment, i. e. for the coarse and fine adjustment; the result of this is uneven wear and inaccurate work.

The present invention overcomes this difficulty in that the swinging movement is used only for the adjustment and that the coarse adjustment is effected by feeding the tool holder on a sliding 20 guide perpendicularly to the axis of the piece to be worked, while the fine adjustment is effected by swinging the swing arm by means of a cam which has the desired eccentricity.

The tool assumes a different height at its end 25 position according to the angle through which it is moved for the purpose of adjustment. In order to avoid this, according to the present invention the device is so arranged that at the end of the feeding movement the swing comes to rest 30 against a stop which is so adjusted that in this position the axes of the grinding spindle and of the spindle for the piece to be worked lie in a horizontal plane perpendicular to the rotation axis of the support for the piece to be worked, there 35 being no play whatever in the rods by which the swing is moved.

The grinding spindle is mounted on a swing arm which is supported by an eccentric pivot located opposite its corresponding chuck which 40 runs in adjustable roller bearings. This allows for the adjustment of the height of the line of contact of the grinding disc and for the play free guiding of the swing.

In order that the invention may be more clearly understood, one particular construction thereof will now be described, by way of example, with reference to the accompanying drawings wherein.

Figure 1 is a side view of the grinding machine, 50 Figure 2 is a part sectional front view, Figure 2a is a side view of the bolt 16 in Figure 2, and Figure 3 is part sectional view of a portion of 55 Figure 1 drawn on a larger scale, and

Figure 4 is a diagrammatic view of the means for driving the disengaging rod.

In these drawings 1 is the bed plate of the machine on which is arranged the spindle box 2 which supports the piece to be worked. The spindle for the piece to be worked which is arranged in bearings in the spindle box, has at its front end a clamping chuck 3 into which is clamped a cylinder block 4 the inner side of which is to be ground. The spindle box is arranged in the usual way on the bed plate 1; it can be displaced longitudinally of the bed plate by means of a slide 44 in order to ensure the forward movement required during the operation of the machine, and can also be swung about a vertical axis 45 for the purpose of adjusting the spindle axis at an angle to the axis of the piece to be worked when it is desired to grind cone-shaped surfaces. As the means for adjusting the spindle box are already known they are not shown in the drawings.

The grinding tool 5 is arranged on the spindle 6 which is held in position by its bearing 7. The bearing 7 together with the spindle and the pulley 8 by which the spindle is driven, form a complete unit which can be dismounted and exchanged. The grinding spindle is driven from a motor 9 by a pulley 10 and a belt 14 which passes over guide pulleys 11, 12 and 13 to the pulley 8 of the spindle. The spindle 6 together with its bearing 7 is mounted in a swing 15 which is supported by a pivot 16. The latter is arranged on a slide 17 arranged on the machine frame and is mounted in two bearings 18 and 19. These are preferably roller bearings and are essentially taper bearings, so that the position can be arranged with utmost precision. The swing 15 is clamped on to the bolt 16 by means of two adjusting screws 20. The bearing pins 21 of the bolt 16 are, as shown in Figure 2a, arranged eccentrically in relation to the axis of the bolt 16, so that by rotating the pins 21 around their axis, the axis of the bolt 16 can be displaced in a circle and, therefore, the swing can be adjusted in this way. The bearing casing 7 carrying the grinding spindle is firmly clamped in its split bearings by a clamp screw 22. A screw 23 is provided as a stop for the swing, which is held against the said stop 23 by the action of a spring 24.

The shaft 52 on which the pulley 11 is arranged carries a worm 51 engaging a worm wheel 59. This worm wheel is mounted on a shaft 54 in such a manner that the shaft may be axially shifted with respect to the wheel but is coupled 110

therewith by means of a key 53 so that the rotation of the worm wheel 59 is transferred to the said shaft. On the same shaft 59 is fastened a gear 50 which in the position shown in Figure 1 meshes with a gear 25 mounted on a vertical shaft. The lower end of the shaft 54 bears against the one end of a lever 55 pivotally journalled in the machine frame about the pivot 56. The other end of the lever 53 bears against the upper end of a rod 36. A spring 57 arranged between a fixed point of the frame and the right hand end of the lever 55 is intended to rotate the lever in an anticlockwise direction. However, it is prohibited from rotating in consequence of its abutment with the rod 36. Another spring 60, arranged between the frame and the upper end of the shaft 53, holds the shaft and the gear 50 in engagement with the gear 25. The means for vertically guiding the shaft 54 and the means for holding the worm wheel 59 on its place when the said shaft 54 is vertically shifted are not shown in the drawings. The gear 25, by means of a pair of bevel gears 26, drives or is driven by a horizontal shaft 27 (Fig. 3), on which is arranged a hand wheel 28. The said vertical shaft, by means of a further set of bevel gears 29, also drives a spiral shaped cam 30. On the cam wheel 30 rests the free end of a cam lever 31, which is pivotally mounted on a shaft 32. On the said shaft 32 is arranged a crank arm 33 which is connected with the swing 15 through a link 34 and an extension 35 of the said swing 15.

The rotating cam 30 pivots the arm 31 slowly, and this causes the shaft 32 to rotate in a clockwise direction. By means of the crank arm 33 and the link 34, the swing is caused to move accordingly, so that, it will swing out to the right in Figure 3 and thus be adjusted in relation to the piece to be worked. On the arm 31 there is also arranged a disengaging rod 36, which is carried with the arm 31 as it drops from the highest part of the cam disc 30, and the gear which drives the gear wheel 25 is thereby disengaged. If the rod 36 drops from the highest part of the cam disc 30, the lever 55 is allowed to be rotated in an anticlockwise direction by means of the spring 57. Thereby the shaft 54 with the gear 50 is raised so that the gear 50 comes out of engagement with the gear 25. The gear 25 is reengaged by rotating the hand wheel 28 whereby the cam wheel 30 is further rotated by means of the bevel gear 26, and the arm 31 and the disengaging rod 36 are again lifted.

As the distance by which the grinding disc is moved forward is comparatively small, the cam disc 30 is so shaped that the first part rises comparatively steeply and serves for moving the grinding disc against the piece to be worked and for adjusting the contact, and serves also for lifting the disengaging rod 36, while the last part of the cam disc has a comparatively slight slope for the purpose of adjusting the thickness of the shaving.

The adjustment screw 37 serves for adjusting the motor 9 for the purpose of tightening the belt 14.

For the purpose of coarse adjustment of the grinding disc 5 the whole slide 17 is adjustable transversely of the spindle on the bed 1. This is effected by means of a hand wheel 38 which by means of a worm gear 39 rotates a perpendicular shaft on which is arranged the gear wheel 40. The gear wheel is in mesh with a rack 41 which is connected with the slide 17.

In order to give absolute precision to the

adjustment of the grinding spindle 6, an adjustable stop 42 is provided against which a cam 43 arranged on the swing abuts when the latter is in its end position. Thus the axis of the grinding spindle in this position will always be at the same height, namely at the height of the axis of the piece to be worked. It is preferable to arrange this in such a way that the swing which supports the tool hangs perpendicularly at the end of the working stroke. This makes it possible, after adjusting the support 2 of the piece to be worked by pivoting it on its perpendicular axis into the desired angular position, to grind a perfect hollow cone, which can be ground accurately only if the plane in which the tool moves forward contains both the axis of the tool and the rotating axis of the piece to be worked. If, as is usual in the grinding of a hollow cone, the plane of rotation of the piece to be worked is horizontal, then in the final position the axis of the piece to be worked and the axis of the tool must lie in the same horizontal plane. Accordingly the movement of the slide 17 is so arranged that it takes place in a plane perpendicular to the rotating axis of the spindle box 2, and also in the direction of the swinging movement of the tool axis 6.

The machine therefore operates as follows:

After the piece to be worked has been clamped in position its support is moved by means of the longitudinal slide 44 to within reach of the tool. The tool is then brought near the inner surface of the piece to be worked by a transverse movement of the tool slide 17, effected by means of the hand-wheel 38. After that, the swinging movement of the grinding spindle can be executed according to the desired forward movement of the grinding spindle in proportion to the amount of abrasion.

The hand wheel 28 is then rotated so that the cam 30 is operated by means of the bevel gear 26 to such an extent, that the arm 31 which is lifted by it, will lift the rod 36 into the engaging position. After this the device will operate automatically. The cam wheel 30 completes its revolution and in doing so moves the swing 15 with the spindle 6, which has been previously moved close to the piece to be worked by hand wheel 28, closer to the piece to be worked for the purpose of removing the filings.

After the operation has been completed the lever 31 will drop from the highest part of the cam 30 and the machine is stopped by the downward movement of the disengaging rod 36. At the same time the swing 15 will be moved back by the action of the spring 24 and lie against the stop 23.

The cam 30 is so arranged that at the end of the operation the swing is pressed against the stop 42 so as to ensure a definite end position.

If it is desired to grind a hollow cone then the spindle box 2 and the axis of the piece to be worked are rotated by an amount corresponding to the angle of the cone. In consequence of the previously described arrangement of the bearings and the adjustment of the spindle 6 an accurate cone can then be ground.

I claim:

1. A machine for grinding the inner surface of cylinders and the like, comprising a bed plate; means on the bed plate for holding and rotating the work piece to be ground; a slide mounted on the bed plate; a swinging arm mounted on the slide; a spindle provided on the swinging arm

and having a grinding tool thereon; means for adjusting the slide transversely of the spindle on the bed plate to adjust the grinding tool for coarse feeding; and means for adjusting the swinging arm for adjusting the grinding tool for fine feeding.

2. A machine according to claim 1, in which the swinging arm is mounted on a pivot eccentrically arranged relative to the swinging axle 10 of the swinging arm and the pivot is mounted in adjustable roller bearings so that the height of the line of contact of the grinding surface can be adjusted.

3. A machine according to claim 1, in which 15 a stop is provided against which the swinging arm abuts at the end of the forward feed movement, the stop being so arranged that in this position the axes of the spindle and the work

piece are in a plane perpendicular to a shaft about which a clamp of the work piece may be turned if a conical grinding is desired.

4. A machine according to claim 1, in which drive means are provided to effect the swinging movement of the arm and in which a cam is provided cooperating with the drive which at the same time disengages the drive at the end of the forward feeding movement.

5. A machine according to claim 1, in which drive means are provided to effect the swinging movement of the arm and in which a cam and a rod mounted on a lever of the cam are provided, whereby the rod disengages the drive when the cam lever falls from the highest point 90 of the cam.
